GREENS FEEDER FOR BIRDS

Leonard Stern, New York, N.Y., assignor to Hartz
Mountain Products Corporation, New York, N.Y., a
corporation of Delaware

Filed Nov. 8, 1960, Ser. No. 62,768

Term of patent 14 years

(Cl. D31—2)

FIG. 2.

FIG. 6

FIG. 5

FIG. 3.

FIG. 1 is a side elevational view of a greens feeder for birds, showing my new design;

FIG. 2 is a top plan view thereof;

FIG. 3 is a rear elevational view thereof.

FIG. 4 is an enlarged fragmentary section of FIG. 3 taken along line 4—4;

FIG. 5 is an enlarged fragmentary section of FIG. 2 taken along line 5—5;

FIG. 6 is an enlarged fragmentary section of FIG. 2 taken along line 6—6, showing the cross-sectional configuration of one of the three identical radial perch-supporting ribs.

I claim:

The ornamental design for a greens feeder for birds, substantially as shown.
